C. R. SHORT,
COMBINED INTAKE AND EXHAUST MANIFOLD,
APPLICATION FILED MAY 28, 1917.

1,406,232.

Patented Feb. 14, 1922.

INVENTOR:
CHARLES R. SHORT,

BY
L. A. C. C. & C. C.,
ATTORNEY.

UNITED STATES PATENT OFFICE.

CHARLES R. SHORT, OF DETROIT, MICHIGAN, ASSIGNOR TO GENERAL MOTORS COMPANY, OF DETROIT, MICHIGAN, A CORPORATION OF NEW JERSEY.

COMBINED INTAKE AND EXHAUST MANIFOLD.

1,406,232.

Specification of Letters Patent. Patented Feb. 14, 1922.

Application filed May 28, 1917. Serial No. 171,492.

To all whom it may concern:

Be it known that I, CHARLES R. SHORT, a subject of the King of Great Britain, and resident of Detroit, Wayne County, State 5 of Michigan, have invented certain new and useful Improvements in Combined Intake and Exhaust Manifolds, of which the following is a specification.

This invention relates to combined intake 10 and exhaust manifolds and more particularly to improvements in gas conducting and distributing passages therefor.

One of the objects of this invention is to provide an improved arrangement and 15 disposition of the induction and exhaust pipes of a hydrocarbon motor.

Another object of this invention is to provide a multicylinder hydrocarbon motor with an intake manifold in which the gases 20 throughout its length are maintained at a substantially uniform temperature thereby assuring an equal density of gas for each cylinder when the motor is in operation.

Another object of this invention is to 25 utilize the heat of the exhaust gases of an internal combustion engine for maintaining the incoming gases at the desired temperature.

Another object of this invention is to provide a combined intake and exhaust manifold, having means for varying the application 30 of the heat of the exhaust gases to the incoming gases, to thereby secure a substantially uniform heating of said incoming 35 gases throughout the length of the intake manifold.

Another object is to provide means for more efficiently vaporizing a hydrocarbon fuel for an internal combustion engine, and 40 for conducting the resulting vapor to the engine.

These, and various other objects will more clearly appear from the following description, taken in connection with the accompanying drawings, which form a part of this 45 specification and in which:

Figure 1 is a side elevation with portions broken away of a hydrocarbon motor cylinder block embodying a preferred form of my 50 invention:

Figure 2 is an elevation with a portion in section of the side of the manifold opposite to that illustrated in Figure 1.

Figure 3 is a transverse section substantially on the line 3—3 of Figure 2.

Figure 4 is a transverse section substantially on the line 4—4 of Figure 2, and

Figure 5 is a transverse section substantially on the line 5—5 of Figure 2. 60

Referring to the drawings, 10 is a six cylinder block for a hydrocarbon motor, provided with over-head poppet valve mechanisms 11 and having arranged adjacent its opposite ends, a pair of exhaust 65 ports 12, and between the end exhaust ports are another pair of exhaust ports 12'. Each end port 12 leads from a single cylinder, and each intermediate port 12' leads to a pair of branches not shown, communicating with 70 adjacent cylinders. The cylinder block is also provided with three equidistantly arranged intake ports 13, each adapted to communicate with a pair of adjacent cylinders.

An intake manifold 14 and an exhaust 75 manifold 15 are formed side by side in an integral casting 16. The intake manifold 14 has formed at one end, an inlet port 17, and equidistantly arranged along its lengths, are outlet ports 18 adapted to register with the cylinder inlet ports 13, when the manifold is in position on the block. 80

The exhaust manifold 15 is formed adjacent its opposite ends and intermediate thereof with four inlet ports 19 which are 85 adapted to register with the exhaust ports 12 and 12' of the cylinder block. This manifold is also provided with an outlet port 20 at the end adjacent to the inlet port 17 of the intake manifold 14, so that the incoming 90 and exhaust gases in the adjacent manifolds flow in opposite directions.

It will also be noted that the gases in each manifold will never change in direction, that is, they are always adapted to 95 flow from one end toward the other. This will eliminate any undesirable tendency to build up a back pressure, and it also facilitates a more uniform distribution and flow of the gases. 100

Adjacent the inlet port 17 and the transversely extending passage 21 of the intake manifold, the exhaust manifold 15 is formed with a larger jacketing surface than at other portions thereof, to thereby accomplish the 105 heating of this portion of the manifold to a higher temperature than other portions thereof. This enlarged heating jacket is particularly illustrated at 15' in Figure 3, and the intake manifold 14 at this loca- 110

tion is also enlarged as at 22, particularly shown in Figure 3 for providing a greater heat absorbing surface, it being appreciated that the intake and exhaust manifolds have 5 a common wall at this enlarged portion of the manifold structure, while beyond this point and throughout the rest of the length thereof said two manifolds although extending substantially parallel with one another 10 are in effect separate and distinct from one another, although they are preferably connected together by the connecting bridges 23 to be hereinafter more particularly referred to.

15 It is of course desirable to prevent the entrance of unvaporized fuels into the intake manifold, and a greater amount of heat should be applied at the manifolds inlet than at any other portion. It will also 20 be understood that as the gases enter the intake manifold their temperature is lowest. Therefore, in order to maintain the temperature of the incoming gases at a substantially uniform temperature throughout 25 the length of the intake manifold and thereby assure an equal volume of gas to each cylinder, I so form and proportion the exhaust manifold 15, relative to the intake manifold 14, that a greater amount of heat 30 is conducted from the former to the latter adjacent its inlet port 17 than at other portions thereof. It is to be noted that both of the manifolds diminish in size from the end in which the manifold inlet port 17 and the 35 outlet port 20 are formed toward their opposite ends. In other words, the heating effect of the exhaust manifold 15 on the intake manifold 14 is at its minimum at the end opposite to the inlet port 17 of the 40 manifold 14.

Distributed along the casting 16 between the intake and exhaust manifolds are a plurality of bridges or heat-conducting members 23 in the form of bosses 24, preferably 45 provided with grooves 25. Bolts 26 are adapted to be passed through suitable orifices extending through these bosses for securing the manifolds in position on the cylinder block, and some of these bridges 50 or connecting members 23 may have the molecular thermal conductivity thereof reduced as by cracking the bridges across from groove to groove, and thus the heating effect will be reduced. It is sometimes found 55 that as a result of a difference in valve timing or in compression or for other reasons, different motors of the same size and equipped with similarly formed and dimensioned manifolds built according to my invention 60 will produce a different heating effect of the gases. This may be adjusted in the manner which I have just described.

The bridges 23 may be broken at the bolt 65 passages which extend through them by fore-ing suitable wedges into said passages, or

by the use of an expanding tool inserted into said passages, or they may be cut apart by means of a metal cutting saw or equivalent cutting implement suitable for the purpose of severing the metallic paths provided by said bridges; and along which paths heat may flow from the exhaust to the intake manifold freely if said bridges are not interrupted as aforesaid, and obviously less freely if and when said bridges are 75 broken or cut across to thereby interrupt their continuity.

While my invention results in many other advantages, my chief object is to provide means for effecting a uniform distribution of 80 gases to the different cylinders, at substantially the same temperature, regardless of the distance between the cylinder inlet port and the manifold inlet port, and this is accomplished by the adjustment of the 85 molecular connection between the intake and exhaust manifolds, whereby the heat conducted from the exhaust manifold to the inlet manifold at various places throughout its length may be controlled. It will also be 90 seen that my construction results in an arrangement wherein the gases of the intake manifold are at all times flowing in the same direction, and a like result is also produced in the exhaust manifold. This produces minimum back pressures.

While I have described and will specifically claim what I deem to be a preferred embodiment of my invention, it will be obvious to those skilled in the art, that various modifications and changes may be made, without departing from the spirit and scope hereof.

Having thus described my invention, what I claim and desire to secure by Letters Patent is:

1. In an internal combustion engine, the combination with a gas intake manifold having an intake port arranged adjacent one end thereof and having a plurality of outlet 110 ports, of an exhaust manifold arranged adjacent to said inlet manifold and adapted to have its thermal conductivity altered to apply a greater or lesser amount of heat to the latter at varying places throughout the 115 length thereof.

2. The combination with an internal combustion engine, of integral intake and exhaust manifolds, said intake and said exhaust each having a port adjacent one end 120 thereof and having a plurality of ports distributed along their respective lengths and a plurality of bosses connecting said intake and exhaust manifolds and adapted to have their thermal conductivity altered to give a 125 desired temperature to said intake manifold.

3. A combined intake and exhaust manifold comprising an intake manifold of graduated cross-section with the larger or inlet end thereof jacketed by the exhaust mani- 130

fold and which manifolds extend beyond said jacketing portion in parallel relation with one another, and are integrally connected together beyond said jacketing portion at predetermined intervals.

4. In combination, an intake and an exhaust manifold arranged alongside and connected with one another at intervals throughout their length by a plurality of bridges formed integrally with the walls of said manifolds, and which manifolds are provided each with a plurality of ports arranged substantially in line and through which communications may be established between the interiors of said manifolds and the cylinders of an engine with which said manifolds are used; and an inlet passage leading into said intake manifold and an exhaust passage leading out from said exhaust manifold, said

20 passages being arranged adjacent one another and both at one and the same end of the structure formed by said manifolds.

5. In combination, an intake and an exhaust manifold arranged alongside and connected with one another at intervals throughout their length through and by means of a plurality of metallic connecting members, and which manifolds are provided each with a plurality of ports arranged substantially 30 in line and through which communications may be established between the interiors of said manifolds and the cylinders of an engine with which said manifolds are used; and an inlet passage leading into said intake manifold and an exhaust passage leading out from said exhaust manifold, said passages being arranged adjacent one another and both at one and the same end of the structure formed by said manifolds.

40 6. In combination, an intake and an exhaust manifold arranged alongside and connected with one another at intervals throughout their length by a plurality of bridges formed integrally with the walls of said manifolds, and which manifolds are provided each with a plurality of ports arranged substantially in line and through which communications may be established between the interiors of said manifolds and the cylinders of an engine with which said manifolds are used; and an inlet passage leading into said intake manifold and an exhaust passage leading out from said exhaust manifold and both of which passages are disposed transverse to the longitudinal axes of said manifolds, said

50 passages being arranged adjacent one another and both at one end and the same end of the structure formed by said manifolds.

7. In combination, an intake and an exhaust manifold arranged alongside and connected with one another at intervals throughout their length by a plurality of bridges formed integrally with the walls of said manifolds, and which manifolds are provided

60 each with a plurality of ports arranged

substantially in line and through which communications may be established between the interiors of said manifolds and the cylinders of an engine with which said manifolds are used; and an inlet passage leading into said intake manifold and an exhaust passage leading out from said exhaust manifold, said 70 passages being arranged adjacent one another and both at one and the same end of the structure formed by said manifolds; the cross-sectional areas of said manifolds being greatest adjacent said passages, and decreasing along the length of said manifolds.

8. In combination, an intake and an exhaust manifold arranged alongside and connected with one another at intervals throughout their length by bridges formed integrally with the walls of said manifold and which bridges are provided each with a hole through which a securing bolt may pass, said manifolds being provided each with a plurality of ports arranged substantially in line and through which communications may be established between the interiors of said manifolds and the cylinders of an engine with 80 which said manifolds are used; and an inlet passage leading into said intake manifold and an exhaust passage leading out from said exhaust manifold, said passages being arranged adjacent one another and both at 90 one and the same end of the structure formed by said manifolds.

9. In combination, an intake and an exhaust manifold arranged alongside and connected with one another at intervals throughout their length by bridges formed integrally with the walls of said manifolds and which bridges are provided each with a hole through which a securing bolt may extend, said manifolds being provided each with a 100 plurality of ports arranged substantially in line and through which communications may be established between the interiors of said manifolds and the cylinders of the engine with which said manifolds are used: 110 and an inlet passage leading into said intake manifold and an exhaust passage leading out from said exhaust manifold, said passages being arranged adjacent one another and both at one and the same end of the 115 structure formed by said manifolds; the cross-sectional areas of said manifolds being greatest adjacent said passages and progressively decreasing throughout the length of said manifolds.

10. In combination, a single integral casting shaped to provide an intake and an exhaust manifold arranged alongside one another and having a common wall throughout a portion of their extent but which manifolds are separate and distinct from one another throughout the greater portion of their length, and which manifolds are provided each with a plurality of ports arranged substantially in line and through 125

130

which communications may be established between the interiors of said manifolds and the cylinders of an engine with which said manifolds are used; and an inlet passage leading into said intake manifold and an exhaust passage leading out from said exhaust manifold, said passages being arranged adjacent one another and both at the ends of said manifolds at which the common wall aforesaid is located.

11. In combination, a single integral casting shaped to provide an intake and an exhaust manifold arranged alongside one another and having a common wall through-

15 out a portion of their extent but which manifolds are separate and distinct from one another throughout the greater portion of their length, and which manifolds are provided each with a plurality of ports arranged substantially in line and through which communications may be established between the interiors of said manifolds and the cylinders of an engine with which said manifolds are used; and an inlet passage 20 leading into said intake manifold and an exhaust passage leading out from said exhaust manifold, said passages being arranged adjacent one another and both at the ends of said manifolds at which the common wall aforesaid is located; the cross- 25 sectional areas of said manifolds being greatest adjacent said passages and progressively decreasing throughout the length of said manifolds.

30 12. In combination, a single integral casting shaped to provide an intake and an exhaust manifold arranged alongside one another and having a common wall throughout a portion of their extent but which manifolds are separate and distinct from one another throughout the greater portion 35 of their length, and which manifolds are

provided each with a plurality of ports arranged substantially in line and through which communications may be established 45 between the interiors of said manifolds and the cylinders of an engine with which said manifolds are used; and an inlet passage leading into said intake manifold and an exhaust passage leading out from said exhaust manifold, said passages being arranged adjacent one another and both at the ends of said manifolds at which the common wall aforesaid is located, and both of them being disposed transverse to the 50 axes of said manifolds.

13. In combination, a single integral casting shaped to provide an intake and an exhaust manifold arranged alongside one another and having a common wall throughout 60 a portion of their extent but which manifolds are separate and distinct from one another throughout the greater portion of their length and are connected with one another by means of metallic bridges located along said last mentioned portion, and which manifolds are provided each with a plurality of ports arranged substantially in line and through which communications may be established between the interiors of said 65 manifolds and the cylinders of an engine with which said manifolds are used, said bridges being provided each with a hole through which a securing bolt may extend; and an inlet passage leading into said intake manifold and an exhaust passage leading out from said exhaust manifold, said 70 passages being arranged adjacent one another and both at the ends of said manifolds at which the common wall aforesaid is located.

In testimony whereof I affix my signature.

CHARLES R. SHORT.
